(57) CLAIM

The ornamental design for a cover for a cleated shoe, as shown and described.

DESCRIPTION

FIG. 1 is a perspective view of a cover for a cleated shoe showing my new design, shown in a position of use with a shoe;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top planar view thereof; and,

FIG. 7 is a bottom planar view thereof showing my design. The broken lines depicting a shoe represent environment that forms no part of the claimed design.
